MEANS FOR SUPPORTING THE NOZZLES OF
THE COMBUSTION CHAMBERS OF INTERNAL-COMBUSTION TURBINES

Arthur Alexander Rubbra, Littleover, Derby, England, assignor to Rolls-Royce Limited, Derby, England, a British company

Application March 8, 1948, Serial No. 13,689
In Great Britain March 14, 1947

4 Claims. (Cl. 60—39.32)

1

This invention relates to gas-turbine-engines of the kind in which a compressor delivers compressed air to a plurality of combustion chambers and the products of combustion flow from the combustion chambers through a ring of nozzle guide vanes or turbine stator blading to one or more turbine rotors which drive the compressor and in which the main structure for supporting the turbine rotor assembly comprises the compressor casing and an intermediate casing lying within the ring of combustion chambers and enclosing the drive shaft between the turbine rotor or rotors and the compressor rotor, and also in which the turbine stator assembly, including shroud ring or rings, stator blading or guide vanes is supported from the intermediate casing.

Hitherto it has been the practice to provide nozzle-boxes between the combustion chambers and the inlet to the turbine, the nozzle-boxes being circular at their forward or inlet ends—where they receive the combustion products from the combustion equipment and substantially rectangular at their rear or outlet ends where they direct the combustion products on to the nozzle guide vane assembly; the outlet ends of the nozzles were arranged side by side to form a complete annular ring corresponding to the annulus of the nozzle guide vane assembly.

In such known constructions the nozzles were welded together along radially abutting edges at their outlet ends and further the inner and outer diametral edges at the outlet ends were welded to inner and outer support rings. With such a construction, it has been the practice to support the inner ring from the intermediate casing referred to, whilst the turbine shroud ring or rings (together with the jet pipe) were supported from the outer ring. As a consequence the weight of the jet pipe was taken through the welded nozzles and also, where the nozzle guide vanes were rigidly secured by welding or otherwise to their inner and outer shroud rings, through the guide vanes.

In the specification of U. S. Patent No. 2,494,821 granted January 17, 1950, there is described a construction in which the nozzle-boxes and nozzle-guide-vanes are relieved of structural loading and which permits of these components being so supported that they can expand freely within the assembly. This construction comprises a ring having a series of apertures each arranged to receive and support the outlet end of a combustion chamber, the apertured ring being secured to the intermediate casing and to the outer ring of the nozzle-guide-vane assembly so that struc-

tural loads are transmitted from one to the other solely through the ring. The ring conveniently provides a wall of a housing which supports the nozzle-boxes. This apertured ring has been produced by a casting operation.

This invention seeks to provide an improved construction of such an apertured ring which is relatively simple to manufacture and which, while retaining the desirable features of a cast construction and a predetermined overall strength, permits a reduction in the weight of the ring.

According to this invention in one aspect, an apertured ring for receiving and supporting the outlet ends of the combustion chambers of a gas-turbine-engine of the kind described, is fabricated by casting and is then machined substantially over its whole surface area by simple turning operations accurately to define the thickness of the ring.

According to this invention in another aspect, an apertured ring for receiving and supporting the outlet ends of the combustion chambers of a gas-turbine engine of the kind described, is in the form of a casting which has been machined substantially over its whole surface so as to have maximum thickness between the apertures and to taper in thickness towards its edges.

In one construction of apertured ring according to this invention, one surface of the ring is machined to the form of a part of a sphere having its centre on the axis of the ring remote from the plane thereof and the other surface of the ring is machined by a turning operation so that the ring has a substantially triangular cross-section between the apertures. Recesses may be formed in the ring between the apertures so that the ring has a web-like formation between the apertures.

By the invention, the weight of the ring may be kept to a minimum having regard to a predetermined overall strength thereof.

According to another feature of this invention, socket members are secured to the ring to engage in the apertures to guide and support the outlet ends of the combustion chambers, and, where the ring is formed with a part-spherical surface, the socket members are preferably each formed with a flange having a spherical surface to co-operate with the spherical surface of the ring.

The invention is particularly applicable to the type of gas-turbine-engine in which the combustion chambers are disposed in a ring around the engine with their axes lying in the surface of a cone the apex of which is beyond the outlet ends of the combustion chambers, and in this case the

centre of the spherical surface of the ring will be the apex of the cone.

There will now be described a gas-turbine-engine of which the nozzle-box assembly comprises one construction of apertured ring according to this invention, the description making reference to the accompanying drawings, in which:

Figure 1 is a side elevation of the gas-turbine engine.

Figure 2 is a fragmentary sectional view on the line 2-2 of Figure 1.

Figure 3 is a fragmentary front view of the apertured ring, and

Figures 4 to 6 are sectional views on the lines 4-4, 5-5, and 6-6 of Figure 3, respectively.

Referring to Figure 1, the jet-propulsion gas-turbine-engine comprises a compressor casing 10 to house a centrifugal impeller which is driven by a single-stage turbine generally indicated at 11. A plurality of combustion chambers 12 receive air from the compressor 10 by ducts 10a and liquid fuel is burnt in these chambers. The products of combustion are delivered to the turbine 11 and then pass to atmosphere by way of an exhaust assembly 13. The exhaust gases are directed rearwardly by the exhaust assembly relative to the direction of flight of the aeroplane for propulsion purposes.

Referring now to Figure 2, it will be seen that the turbine shaft 14 supports the turbine disc 15 which carries blades 16. The shaft 14 is supported by a bearing 17 carried by a structure 18 extending from an intermediate casing 19 which is bolted to the compressor casing 10. In this way the turbine rotor assembly is supported from the compressor casing 10, the intermediate casing 19 and the structure 18 constituting a "back-bone" structure for the engine.

The exhaust assembly 13 is bolted at 21 to a turbine shroud ring 22 which in turn is bolted at 23 to an outer ring 24 between which and an inner ring 20 extend the fixed guide vanes 25 of the turbine.

A ring 26, forming one part of a labyrinth seal, is bolted to the inner ring 20 which is itself bolted at 27 to a tubular member 28.

A nozzle-box assembly is located between the outlet ends of the combustion chambers 12 and the guide vanes 25. The nozzle-box assembly comprises a ring-like casting 29 having an apertured forwardly-facing wall 29a by which the outlet ends of the combustion chambers 12 are supported and a series of nozzle-boxes 30 which are supported at their inlet ends by the casting 29 to receive the combustion gases from the combustion chambers and which are supported at their outlet ends in between a flanged ring 31 and the tubular member 28. It will be understood that the nozzle-boxes are circular at their inlet ends and are substantially rectangular at their outlet ends to abut laterally to form a substantially annular outlet to the guide vanes 25.

The casting 29 is formed with an outer peripheral wall 29b which extends rearwardly and inwardly to be bolted at 32 to the flange 31a on the ring 31 and the outer ring 24 of the guide vane assembly, and with an axial, forwardly-directed flange 29c at its inner periphery which is bolted at 33 at its front end to the intermediate casing 19 and structure 18 and at 34 at its rear end to the tubular member 28. In this way loads applied to the turbine shroud ring 22 by the exhaust assembly 13, for example due to its weight, are transmitted through the outer ring 24 of the

guide-vane assembly to the casting 29 which transmits them to the intermediate casing 19. These parts constitute the main load carrying structure of the engine and the tubular member 28 and inner ring 20 which support the guide blades 25 are substantially unstressed. The guide blades 25 are arranged to be located circumferentially by the outer ring 24 but to have radial freedom with respect to the ring so that any loads on the rings 20, 24 are not imparted to the blades.

The nozzle-boxes 30 are provided at their inlet and outlet ends with springy flanges 35 by which they engage with the casting 29 and the parts 31 and 28 so that the nozzle-boxes are also substantially free from loads in the main engine structure.

The combustion chambers 12, which are disposed in a ring around the shaft 14, have their inlet ends at a greater radius than their outlet ends and the axes of the combustion chambers lie in the surface of a cone having its apex 36 on the shaft axis and the apertured wall 29a of the casting 29 is arranged to be substantially normal to the axes of the combustion chambers.

Referring now to Figures 3 to 6, which illustrate the casting 29 in detail, it will be seen that the casting 29 is formed with a series of circular apertures 37 which are machined to have a cylindrical periphery and therefore to lie substantially in a plane which is normal to the axis of the combustion chamber associated with it.

The wall 29a is machined on its inner surface 38 to be part of a sphere having its centre at the apex 36 of the cone in the surface of which the combustion chamber axes lie.

The outer surface 39 of the wall 29a is also machined by a simple turning operation about the axis of the ring 29 so that the wall 29a thereof has a thickness predetermined in relation to the part-spherical surface 38. It is arranged that the minimum thickness is obtained in the areas lying beyond the apertures 37, that is in the peripheral areas of the wall 29a and that the thickness is increased in the region between the apertures in order to increase the strength of the ring where it is weakened by the presence of the apertures 37. As will be seen more clearly from Figure 5, the wall 29a has its maximum thickness between the apertures 37 and tapers smoothly towards its peripheral edges so as to have a substantially triangular radial cross-section between the apertures.

In order to avoid giving the ring an excessive weight due to the increase in thickness between the apertures, the ring 29 is preferably cast with recesses 40 in the thickened portion so that the metal between each pair of apertures is in effect constituted by webs (see Figure 6) bounding the apertures circumferentially. It will be appreciated that this web-like formation gives the ring 29 an increased resistance to bending whilst avoiding excessive weight of the ring.

Reinforcing socket members 41 are located in the apertures to provide cylindrical surfaces 42 and 43 forming guides and sealing surfaces respectively for the outlet ends of the combustion chambers and the inlet ends of the nozzle boxes. Each socket member 41 is formed with a peripheral flange 44 having one surface of spherical form to co-operate with the surface 38 of the wall 29a and the socket members 41 are secured in position by studs 45 extending through the wall 29a into the flanges 44. Flats 46 are machined on the front surface 39 of the wall to provide a seating for the heads of the studs 45.

The outer peripheral wall 29b and the inner peripheral flange 29c may also be machined to a desired thickness by a simple turning operation about the ring axis.

I claim:

1. An axial-flow gas-turbine comprising a turbine rotor; a stator casing enclosing the rotor; a driving shaft on said turbine rotor; a plurality of combustion chambers disposed in a ring around the said shaft with their axes intersecting the turbine axis all at a single point; an intermediate casing surrounding the shaft within the ring of combustion chambers; a ring-like casing member connected to the intermediate casing and to the stator casing to transmit structural loads therebetween, said ring-like casing member having one machined surface formed as a portion of a sphere whose centre lies at said point, and having formed therein a plurality of apertures, one aperture for each combustion chamber spaced circumferentially to correspond with the disposition of the outlet ends of the chambers, the angular position of said ring-like casing member being such that the axes of the combustion chambers intersect at said point, said ring-like casing member having a second machined surface opposite to said first machined surface, said second surface being of substantially non-uniform convex contour so that the said two surfaces cooperate to provide the greater thickness of the ring-like casing member in the region lying between said apertures and the less thickness in the peripheral regions of the ring-like casing member, and a plurality of apertured socket members one in each of said apertures to receive and support the outlet ends of the combustion chambers, said socket members each being secured to said casing member on the spherical side thereof by flange means formed on the socket member.

2. An axial-flow gas turbine as claimed in claim 1 wherein the socket members are formed with a flange having a surface machined to be part of a sphere to co-operate with the spherical surface of the ring.

3. An axial-flow gas turbine as claimed in claim 1 wherein the cross-section of the portion

of the ring-like casing member lying between the apertures, on a plane forming the surface of a cone whose axis is the axis of the turbine, is of U-shaped form.

5. 4. An axial-flow gas-turbine comprising a turbine rotor; a stator casing enclosing the rotor; a driving shaft on said turbine rotor; a plurality of combustion chambers disposed in a ring around the said shaft; an intermediate casing 10 surrounding the shaft within the ring of combustion chambers; a ring-like casing member connected to the intermediate casing and to the stator casing to transmit structural loads therebetween, said ring-like casing member having one machined surface formed as a portion of a sphere whose centre lies on the axis of the turbine, and having formed therein a plurality of circumferentially spaced apertures, one aperture for each combustion chamber, said ring-like 15 casing member having a second machined surface opposite to said first machined surface, said second surface being of substantially non-uniform convex contour and cooperating with said first machined surface to define areas of greater thickness of the ring-like casing member between said apertures and of relatively less thickness in the peripheral areas of the ring-like casing member, and a plurality of socket members one in each of said apertures to receive and support the 20 outlet ends of the combustion chambers, said socket members each being secured to said casing member on the spherical side thereof by flange means formed on the socket member.

35 ARTHUR ALEXANDER RUBBRA.
